UNITED STATES PATENT OFFICE.

HARRY D. PURSELL, OF WASHINGTON COURT-HOUSE, OHIO.

ADVERTISING AND DISTRIBUTING APPARATUS.

SPECIFICATION forming part of Letters Patent No. 424,354, dated March 25, 1890.

Application filed December 19, 1889. Serial No. 334,285. (No model.)

To all whom it may concern:

Be it known that I, HARRY D. PURSELL, a citizen of the United States, and a resident of Washington Court-House, in the county of Fayette and State of Ohio, have invented certain new and useful Improvements in Advertising and Distributing Apparatus, of which the following is a specification.

My invention relates to that class of vending apparatus which are set in operation by dropping a coin in a slot, which releases a catch, operates a spring, and delivers the package, and at the same time displays an advertisement or design.

The objects of my invention are to provide novel means for releasing the spring-projected package-delivering shelf and to provide novel means for exposing the advertisement by the movement of the shelf. To accomplish these objects my invention involves the features of construction, the combination or arrangement of devices, and the principles of operation hereinafter described and claimed, reference being made to the accompanying drawings, in which—

Figure 1 is a central vertical section of my improved apparatus. Fig. 2 is a section on line *xx*, Fig. 1. Fig. 3 is a section on line *yy*, Fig. 1. Fig. 4 is a front elevation of the advertising mechanism.

1 represents the package-casing. It is provided with compartments 2, 3, and 4. The compartments 3 and 4 are separated from the compartment 2 by means of the sliding partition 5, the front portion of which is employed as a delivering-shelf, which is shown in the open position in dotted lines, Fig. 1. This delivering-shelf is provided with a recess 6 of a sufficient depth, size, and contour to receive the package to be delivered. The sliding shelf is operated by means of one or more springs 7, which are shown in the preferred form as having a coil 8, with a hook end 9 engaging in the rear end of said partition or shelf. I prefer to employ two or more springs, so as to apply the force near both sides of said shelf uniformly. This shelf is held in the normal position shown in Fig. 1 against the force of the spring by means of the flexible bar 10, which engages behind a spring-catch 11. (See Figs. 1 and 3.)

12 represents a push-button, which is held in the normal position by means of the spring 13. Said push-button can be pushed in normally without reaching the flexible bar 10; 55 hence the spring cannot be tripped by means of the push-button itself. The side of the case is recessed to form a coin-conduit 14 sufficiently deep to admit the passage of the coin, the face of said recess being closed with a 60 thin strip of wood *a*. Said coin drops down into position shown in Figs. 2 and 3 and in dotted lines, Fig. 1, in front of the push-button 12. When this button is pushed in, the flexible bar 10 is pushed inward past the 65 spring-catch 11, when the force of the springs 7 is free to act upon the said shelf 5 and immediately forces it out into the position shown in dotted lines, Fig. 1. If the compartment 4 contains packages of the proper shape, one of 70 said packages rests in the recess 6 and is carried forward with the movement of the shelf into position.

To set the machine the shelf is pushed back by hand, so that the flexible strip re-engages 75 against the spring-catch 11. In order to display the advertisements, I provide a rod 16, which is journaled in eyes 17 on the inside of the rear wall of the case. To the bottom of said rod 16 is attached a cord 18, passing up 80 through eyes 19, and is attached to the shelf at 20. From the top of said rod 16 is attached any card or device calculated to attract attention. I have shown the advertising-card 21 as attached to the rod 16, so that the word 85 "Gum" shows when the shelf is in its normal position. When the shelf is moved outward by the springs 7, the cord 18, being attached to the free end of the rod 16, places the card up as the shelf goes out until the card 21 is 90 raised up in the position shown in dotted lines 22, Figs. 1 and 4, exposing the entire device.

The device is operated as follows: The packages are put in compartment 4 when the shelf 5 is in its normal position, the word "Gum" 95 on the advertising-card only showing. When the coin 15 is dropped in through the slot, it drops to the bottom of the said strip 10, which has sufficient retractile force to hold the nickel clamped at the bottom in front of the push-button, when the button 12 is pushed, carrying the flexible strip outward and releasing

its engagement with the spring 11, and shelf 5 is pushed outward, as shown in dotted lines, Fig. 1. The retreat of the button through the recoil of the spring 13 allows the coin to drop 5 through into the compartment 2. As soon as the package is delivered the shelf 5 is pushed back by an attendant, and the advertising-card will drop by gravity of the rod and conceal the design within the compartment 3, the 10 spring-catch 11 engaging with the flexible strip 10, ready for a second operation.

It is obvious that more or less of the advertising-card can be shown or that the attachment of the spring could be reversed and the 15 advertisement exposed when the drawer is closed and withdrawn when the drawer is open, or vice versa.

Having described my invention, what I claim is—

20 1. The combination, in a vending apparatus, of a case, a package-delivery shelf having a projecting flexible bar, a spring for throwing the shelf outward, a catch on the case for engaging the flexible bar and holding the shelf 25 against the tension of the spring, a coin-con-

duit for conveying a coin beside the flexible bar, and a push-button for causing the coin to press the flexible bar from engagement with the catch, substantially as described.

2. The combination, in a vending apparatus, 30 of a movable shelf, a spring for throwing the shelf outward, a lengthwise-moving rod for carrying an advertisement, and a cord connected with the rod and shelf for moving the rod lengthwise as the shelf moves outward, 35 substantially as described.

3. The combination, with a case, a spring-impelled shelf, and a catch, of a push-button and a flexible bar engaging the catch and connected with the shelf and arranged relatively 40 to the inner end of the push-button to provide an intervening coin-receiving space, substantially as described.

In testimony whereof I have hereunto set my hand.

HARRY D. PURSELL.
